UNITED STATES PATENT OFFICE.

HERSCHEL M. CONNOR AND DON D. MILES, OF SAN FRANCISCO, CALIFORNIA.

AUTOMATIC CIRCUIT-BREAKER FOR COIN-CONTROLLED TELEPHONE SYSTEMS.

1,262,645.

Specification of Letters Patent. Patented Apr. 16, 1918.

Application filed February 20, 1917. Serial No. 149,837.

To all whom it may concern:

Be it known that we, HERSCHEL M. CONNOR and DON D. MILES, citizens of the United States, residing at San Francisco, in the county of San Francisco and State of California, have invented certain new and useful Improvements in Automatic Circuit-Breakers for Coin - Controlled Telephone Systems; and we do hereby declare the following to be a full, clear, and exact description of the invention, such as will enable others skilled in the art to which it appertains to make and use the same.

This invention relates to automatic circuit breakers for coin controlled telephone systems and has for its object to provide a device of this character which will prevent subscribers from getting connections by grounding the line as well as a device which will be simple in construction, comparatively inexpensive to manufacture and to install, and one that will be more efficient in action than those heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views:—

Figure 1 is a diagrammatic illustration of the usual coin controlled telephone circuit, showing this invention employed therein;

Fig. 2 is a detail elevational view of one form of magnet and armature with the invention applied thereto;

Fig. 3 is an enlarged detail sectional view partly in elevation of a portion of the parts illustrated in Fig. 2;

Fig. 4 is a view similar to Fig. 3 but showing the parts in a somewhat different position;

Fig. 5 is an end elevational view of the armature shown in Figs. 3 and 4;

Figs. 6, 7 and 8 are respectively central sectional, side, and end elevational views of a slightly modified form of the armature shown in Fig. 2;

Fig. 9 is a sectional plan view of a still further modified form of the invention; and

Fig. 10 is a side elevational view of a still further modified form of the invention especially adapted to a somewhat different type of relay.

1 indicates a battery or other source of current at the central station, 2 the operators signal lamp having a filament 3, connected as at 4 to the wire 5 joining the battery 1 and the magnet or relay coil 6, the latter associated with the armature member 7, see Fig. 3, carrying the spring member 8, secured as by the screw 9 to the said armature 7, which is conveniently pivoted as at 10 to the base or support 11. The said spring member 8 is provided with the tip or contact member 12 and with the adjustable make and break contact 13, while the armature 7 is provided with the contact 14 adapted to make circuit with said contact 13. A spring 15 conveniently secured to the armature 7 by the screw 9, carries the adjusting screw 16, contacting with the spring 8 and serving to regulate the pressure between the contacts 13 and 14.

The filament 3 is also connected as by the wire 20 to the contact 40 carried by the coil 6, while the armature 7 and base 11 are connected by the wire 21 to the ground 22. 23 represents a coin at the subscribers station after having been deposited and closed the circuit between the contact members 24 and 25, the latter being connected to the ground 26, and the former 27 through the wire 27, coils 28 and wire 29 being connected to the main line 30. The battery 1 is grounded as at 31.

In a coin controlled telephone circuit of the nature just described, were no spring 8 and make and break contacts such as 13 and 14 provided, it is evident that a dishonest patron could, by grounding the main line 30 as at any point 32, between the subscriber's coil 28 and the central station, or by grounding the connections as at any point 33 between said coils and the central station, readily cause the operator's lamp 2 to light up without the prepayment of a coin 23, for in such cases the current would readily flow from the battery 1 to the ground 31, to the grounds 34 and 35 as the case may be, over the main line wire 30, or over the connection 29 and main line 30 to and through the coils 6 of the magnet or relay at the central station, along the wire 5 to the point 4 and back to the battery 7.

Prior to our invention the armature 7 of the magnet coil 6 has been included in the local circuit of the operator's lamp 2, just as is the case here, but in such a manner as to positively close the said circuit when cur-

rent is passed through the said coil 6, irrespective of the strength of energizing current in said coil. That is to say, the said armature 7 has been provided with a single contact member corresponding to the contact 12 adapted to make circuit with a stationary contact member similar to the member 40 there illustrated, but no contacts corresponding to the members 13 and 14 have been provided. In said prior devices, upon the energization of the coil 6, in the manner above disclosed, the said local or lamp circuit would be closed through the said armature and stationary contacts corresponding to the members 12 and 40, and current would in that case flow from the battery 1 to ground 31, ground 22, along wire 21 to armature 7, to the contact corresponding to member 12 and to contact corresponding to member 40, along wire 20 through lamp 2, and back to battery 1, thus lighting said lamp. But, as above pointed out, no contacts corresponding to the members 13 and 14 being included in said local circuit, the lamp 2 would light whether or not the strength of the current through the coils 6 was greatly varied. In other words, a dishonest subscriber could by grounding the main line at say the points 32 and 33 cut out the resistance of his coils 28, and the central station signal lamp 2 would still light up and connection would be given him.

By our invention comprising the contacts 13 and 14 and adjustable spring 8, on the other hand, a dishonest subscriber cannot thus cheat the telephone company, for when he grounds the main line or any of its connections at any point which will cause a great change of resistance in the circuit the lamp 2 will fail to give a signal, and no connection will be given by the operator. That is to say, should the subscriber introduce too much resistance in his connection to ground at points such as 32 and 33, the armature 7 will fail to make contact between the members 12 and 40, and no signal will be given by the lamp 2. And should he introduce too little resistance in said connection or none at all, the armature 7 will be so strongly attracted by the magnet 6 that the spring 8 will be forced away from said armature and the circuit broken at said contacts 13 and 14, with the result again that no signal appears. It is not practicable for the subscriber to determine just how much or how little resistance would exactly balance the resistance of his coils 28, and even if he should get this knowledge the strength of the battery current could be readily changed at the central station, or the normal pressure between the contacts 14 and 13 could be readily changed and thus foil any dishonest attempts of that kind.

65 When an abnormal current passes through

the coils 6 by reason of attempts to cheat the system in the manner above disclosed or through other causes, the end 60 of the spring 8 may be received against the insulation 61 with which the armature 7 is provided, and thereby prevent shunting out of the circuit the contacts 13 and 14, while at the same time permitting the circuit through said contacts to be broken all as will be clear from Fig. 4.

70 In the modified form of armature shown in Figs. 6, 7 and 8, the spring 8 is omitted, a coiled spring 65 is substituted, a slideable adjustable screw member 66 carrying the contact 12 is provided, and the insulation 67 rigid with the member 66, may slide piston like in the tubular insulation 68 to make and break the circuit at the contacts 13 and 14 carried by the member 69 and the armature 7 respectively. Said member 69 is carried by the slideable adjustable member 66 as will be clear from Fig. 7.

75 In the further modified form of the invention shown in Fig. 9, the contacts 13 and 14 are still in series with the contacts 12 and 40, but they are not carried by the armature 7, as in the preceding case. In this figure, the contact 14 is carried by the member 70 connected to the wire 20, the contact 13 is carried by the adjustable spring 80 member 71 controlled by the screw 72, and the contact 40 is also carried by said member 71. The contact 12 is carried by the adjustable screw 73 in electrical connection with the armature 7.

80 In the still further modified form of the invention shown in Fig. 10, the frame member 75 is insulated as at 76 from the member 77 carrying the contact 40, and joined to the wire 20 as illustrated. The movable contact 12 is carried by the spring member 78 adapted to be fixed or moved by the extension 79, of the armature 80 and to break circuit between the contacts 81 and 90, respectively carried by the spring members 82 and 78. The spring member 82 controls with the adjustable screw 83 carried by the spring 84. The said spring member 82 is joined to the wire 21, and the members 77, 78, 82 and 84 are insulated from each other 85 as shown in the drawings.

85 The operation of our invention will be clear from the foregoing but may be briefly summarized as follows:

90 Referring more especially to Figs. 1 and 2, it will be observed that there are two pairs of contacts 12 and 40, and 13 and 14, which are in series and that whenever the current on the main line 30 becomes abnormally strong, as by grounding the same as 95 at 32, in an effort to cheat the telephone company, the armature 7 will be so moved as to break circuit between the contacts 13 and 14 and therefore the signal lamp 2 in the central station will fail to light up and 100

accordingly, the dishonest subscriber will fail to get his connections. It will further be seen in all the forms illustrated, there is likewise a pair of contacts corresponding to the contacts 12 and 40 and 13 and 14 just mentioned and that in every case whenever the current through the coils or relay magnets 6 becomes abnormally strong, the armature is moved to such a distance as will 10 first make circuit between contacts 12 and 40, and upon a further movement of said armature, due to an abnormally strong current, it will then break circuit between the other pair of contacts in series with said 15 first mentioned contacts 12 and 40, and in such event that the signal lamp fails to light.

It is obvious that those skilled in the art may vary the details of the construction as 20 well as the arrangement of parts without departing from the spirit of the invention and therefore we do not wish to be limited to the above disclosure except as may be required by the claims.

25 What we claim is:—

1. In an electro-magnet signaling device the combination of an armature; a spring carried by said armature; a plurality of contacts in series carried by said spring; a 30 contact independent of said armature coacting with one of said spring carried contacts; a contact carried by said armature coacting with another of said spring carried contacts; and adjustable spring controlled means for holding said last named 35 pair of contacts normally in their closed positions, substantially as described.

2. In an electro-magnetic signaling device the combination of an electro-magnet; 40 an armature associated with said magnet; a contact member associated with said magnet; a second contact member associated with said armature; a spring associated with said armature; a third contact member controlled by said spring adapted to 45 make and break circuit with said first named contact member; a fourth contact member also controlled by said spring and

joined in series with said third contact member adapted to make and break circuit 50 with said second named contact member; and adjustable means for holding said second and fourth members normally in contact with each other, substantially as described. 55

3. In an electro-magnetic signaling device the combination of an electro-magnet; a contact member; an armature; a second contact member controlled by said armature; a spring; a third contact member controlled by said spring adapted to make and break circuit with said first named contact member; a fourth contact member also carried by said spring in series with said third contact member adapted to make and break 60 circuit with said second contact member; and adjustable means coacting with said spring for holding a pair of said members normally in contact with each other, substantially as described. 65

4. In an electro-magnetic signaling device the combination of a contact member; a second contact member adapted to make circuit with said first named contact member; a spring member carrying said second 70 contact member; an armature adapted to move said spring member and make circuit between said contact members; a third contact member also movable with said armature; a fourth contact member for closing 75 the circuit with said third contact member; a second spring member carrying said fourth contact member; an adjustable means contacting with said second spring member for normally maintaining the circuit closed between said third and fourth contact members; and a third spring member carrying said adjustable means, substantially as described. 80 85

In testimony whereof we affix our signatures, in presence of two witnesses.
